UNITED STATES PATENT OFFICE.

VINTON E. SISSON, OF CHICAGO, ILLINOIS, ASSIGNOR TO WALTER P. MURPHY, OF CHICAGO, ILLINOIS.

CENTERING DEVICE.

1,080,723.

Specification of Letters Patent.

Patented Dec. 9, 1913.

Application filed August 31, 1911. Serial No. 646,998.

To all whom it may concern:

Be it known that I, VINTON E. SISSON, a citizen of the United States, and a resident of the city of Chicago, in the county of Cook and State of Illinois, have invented a new and useful Improvement in Centering Devices, of which the following is a specification.

My invention relates to centering devices for railway draft rigging, and more particularly to an improved center or striking-casting and carry iron for the draw bar and means for supporting the latter in longitudinal alinement with the center line 15 of the car while permitting such lateral movement of the same as service conditions require.

My invention further relates to improvements in the design of the striking-casting 20 to adapt it to the requirements of modern high capacity cars and consequent heavy shocks; to the particular design and arrangement of links and carry iron whereby a quick return of the draw bar to its central 25 position is effected and the strain and wear on the parts are at the same time kept from becoming excessive; and to the improvements in the design and arrangement of these parts more fully set forth in the following description of the embodiment of my invention illustrated in the accompanying drawings.

In the drawings,—Figure 1 is a view in front elevation of a portion of an end sill 35 of a car provided with my improved arrangement of striking-casting and draw bar carry iron; Fig. 2 is a part top plan view and part horizontal section of the same on the line 2—2 of Fig. 1; Fig. 3 is a vertical section through my improved device along the center line of the car, showing the end sill and a portion of the car under framing; Fig. 4 is a vertical section of the same on the line 4—4 of Fig. 1; Fig. 5 is a part 45 vertical section of the striking-casting on the line 5—5 of Fig. 3; Fig. 6 is a vertical section of the same on the line 6—6 of Fig. 5; Fig. 7 is a top plan view of the carry iron, partly in section; Fig. 8 is an isometric 50 view of a link; Fig. 9 is a partial top view of a modified form of carry iron; Fig. 10 is a part side elevation; and Fig. 11 is an end view of the same.

Referring to the drawings, in which like 55 characters designate like parts wherever

they occur, I have illustrated a portion of the end framing of a car, comprising the end sill 1, and the longitudinal draft sills or girders 2 attached to the end sill by means of an angle 3 to which each is riveted. The 60 draft rigging is carried by these girders 2, the draw-bar 4 projecting through and under the striking-casting 5 and having its outer extremity supported on the carry-iron 6. The outer extremity of the draw-bar 65 must be free to move transversely to the center line of the car, but must be maintained at an approximately fixed elevation, and should be returned to central alinement after having been thrown out of line, in 70 order to be in proper position to automatically couple with another car, and it is the function of the centering device to enable the draw-bar to accommodate itself to these conditions.

My improvement consists in supporting the carry-iron 6 on the short links 7 pivotally mounted in its bifurcated or slotted ends by means of pins 8. These links are provided with trunnions 9 at their upper extremities, which trunnions are supported in bearings 10 formed in bifurcated portions 13 of the striking-casting 5, which extends down on both sides of the draw-bar. The trunnion form of link does away with a 85 number of parts of and provides larger bearing surfaces than a plain link with eyes and pins. The links themselves are arranged within the space 11 between the bifurcations 13, and are readily inserted in or 90 removed from position. The carry-iron 6 is provided with lugs 12 positioned one on either side of its top surface, which serves as a bearing for the draw-bar, and said lugs are adapted to position the draw-bar centrally on the carry-iron. These lugs 12 are arranged to extend partly into the space 11, in which space they fit loosely, thereby preventing the carry-iron from tipping or rocking in and out as the draw-bar is pulled out and pushed in under varying conditions of draw-bar pull, and saving the links from having to withstand a large part of the shocks tending to bend or twist them. I find I can use shorter links having a quicker 95 action than would be possible were the lugs 12 not provided.

In the modified form of carry-iron 19 illustrated in Figs. 9, 10 and 11, the lugs 20 which engage between the bifurcations of 110

the downward projecting portions 13 of the striking-casting are placed near the ends of the carry-iron and partly slotted to receive the supporting links 7. This arrangement enables a shorter carry-iron to be used than would otherwise be possible, and provides for greater lateral swing of the carry-iron before the walls of the slotted lug 20, pass from between the walls of the opening 11. This allows greater lateral movement of the draw-bar which is very desirable since it reduces wheel-flange wear and side strain on the draw-bar when cars are rounding curves.

The striking casting is provided with a top flange 14 for attachment to the end sill, and an inner flange 15 fitting the contour of the draw-bar recess in the end sill, and between these two flanges is a channel section 16 stiffened with webs. This channel 16 forms a bridge across the ends of the girders 2, and serves to receive impact shocks due to collisions with other cars and distribute them so that they may be the better carried by the car framing. To further strengthen the connection between the striking-casting and car framing, the striking-casting is riveted not only to the end sill, but to the draft girders also by the rivets 17, and to the angles 3 by the rivets 18, thus making a very rigid structure to receive the blows from colliding with other equipment. Moreover, as the points of attachment of the striking-casting to the end sill are substantially in longitudinal alinement with the draft girders, and the lugs 12 of the carry-iron engage the striking-casting substantially in longitudinal alinement with the draft girders, draw-bar shocks coming on the carry-iron will be transmitted to the draft girders direct, without subjecting the carry-iron supports to bending or twisting strains, and without any tendency to distort the end sill. Thus I am able to secure the advantages of the pivotal link connection for supporting the draw-bar without the disadvantages of this arrangement as heretofore used, for the complex bending stresses to which these parts were formerly subjected, and which soon resulted in failures in these parts, I have taken care of with my improved arrangement by transferring them to other members amply strong to carry them without failure.

I do not wish to be limited to the precise forms and dimensions shown, but

What I claim and desire to secure by Letters Patent is as follows:

1. The combination with a recessed end sill of a center casting having an external flange adjacent the end sill and adapted to be attached thereto, an internal flange following the contour of the recess of the end sill to position the casting with respect thereto, bifurcations symmetrically arranged on either side of the center line of the cast-

ing, pivoted links mounted between said bifurcations with their pivotal axes parallel to the center line of the car, and a carry-iron pivotally supported by said links, said carry-iron being provided with lugs engaging between the bifurcations in said casting. 70

2. A centering device for railway draft rigging comprising a center casting having a central passage for the draw-bar formed between two bifurcated projecting portions, 75 bearings in said bifurcated portions, links having trunnions, said links being suspended by said trunnions on said bearings to swing between said bifurcations, and a carry-iron pivotally supported by said links. 80

3. A centering device for railway draft rigging comprising a center casting having two bifurcated projecting portions forming a central passage for the draw-bar, bearings in said bifurcated portions, links pivotally mounted in said bearings to swing between said bifurcations, and a carry-iron pivotally supported by said links, said carry-iron having parts adapted to slidably engage between said bifurcations. 85 90

4. The combination with spaced longitudinal draft girders and an end sill, of a striking-casting secured to said end sill and to said draft girders to form a rigid bridge across the ends of said draft girders, and a carry-iron supported from said striking-casting for movement in a transverse direction with respect to the car, said carry-iron being provided with parts adapted to slidably engage with transverse walls of said striking-casting at points substantially in longitudinal alinement with said draft girders. 100 105

5. In a centering device for railway cars, a carry-iron, supporting links pivotally connected to said carry-iron at its ends, said links being provided with trunnions at the ends remote from said carry-iron, and a striking-casting having depending portions on its under side terminating over the ends of said carry-iron, said striking-casting having notches forming part bearings for said trunnions, the depth of the notches being greater than the space between the ends of the carry-iron and the under side of the depending portions of the striking-casting so that the links cannot be raised sufficiently for the trunnions to clear the sides of the notches in any position of the carry-iron. 110 115

6. A swinging carry-iron for draw-bars of railway cars arranged for movement crosswise of the car, the ends of said carry-iron having sliding engagement with portions of the car depending on both sides of the draw-bar and spaced therefrom, thereby preventing movement of the carry-iron lengthwise of the car. 120 125

7. In a railway car, a gravity centering and supporting device for draw-bars, said device being hung from the striking-casting 130

- by links provided with trunnions, and lugs on said draw-bar supporting device which slidably engage notches provided on the striking-casting.
- 5 8. In a carrier for the laterally movable ends of draw-bars, a draw-bar support having bifurcated ends which slidably engage in notches provided in fixed portions of the car, and supporting links pivoted between 10 said bifurcations, said supporting links being provided with trunnions seated in bearings in fixed portions of the car.
9. In a carrier for draw-bars, a laterally movable carry-iron suspended from bearings on a fixed portion of the car, the ends 15 of said carry-iron extending vertically on both sides of the draw-bar and slidably en-
- gaging in notches in fixed portions of the car, whereby movement of the carry-iron longitudinally of the car is prevented. 20
10. In a carrier for draw-bars, a carry-iron pivotally supported from bearings on a fixed portion of the car, said carry-iron having lugs on its upper surface slidably engaging in notches in fixed portions of the 25 car and adapted to maintain a draw-bar in central position on said carry-iron.

Signed at St. Louis, Missouri, this 28th day of August, 1911.
